Filed Apr. 30, 1964, Ser. No. 79,759

Term of patent 14 years

(Cl. D55—1)

Fig. 1

Fig. 2

FIGURE 1 is a front perspective view of a machine tool base and bed unit showing my new design;

FIGURE 2 is a side elevational view thereof, the opposite side being a mirror image thereof;

FIGURE 3 is an end elevational view thereof, the opposite end being a mirror image thereof;

FIGURE 4 is an end elevational view of the inner end of either of the base elements thereof; and

FIGURE 5 is a top plan view thereof.

The broken line showing of power heads in FIG. 2 is for illustrative purposes only.

I claim:

The ornamental design for a machine tool base and bed unit, as shown and described.
